UNITED STATES PATENT OFFICE.

ROBERT RICHARD KING, OF RICHMOND, VIRGINIA.

ACCOUNTING-SHEET.

1,323,226.

Specification of Letters Patent. Patented Nov. 25, 1919.

Application filed April 26, 1919. Serial No. 292,961.

To all whom it may concern:

Be it known that I, ROBERT RICHARD KING, a citizen of the United States, residing at Richmond, in the county of Henrico and State of Virginia, have invented certain new and useful Improvements in Accounting-Sheets; and I do hereby declare the following to be a full, clear, and exact description of the invention, such as will enable others skilled in the art to which it appertains to make and use the same.

This invention relates to accounting sheets, and has for an object to provide a sheet of the "loose leaf" ledger type so ruled as to present a substantially blank space corresponding substantially in size to an accompanying statement sheet, which sheets are intended to be attached together and filed away during the period covered by the statement sheet; the said sheets being properly ruled and designated to receive corresponding data, one from the other.

A further object of the invention is to provide a statement sheet properly ruled and designated to receive from time to time during a predetermined period, entries of transactions, including items and amounts, together with a ledger sheet having a substantially unruled space approximating the size of the statement sheet, with another portion properly ruled and designated, to be visible when the statement sheet is superposed thereon, presenting spaces for receiving totals from the statement sheet as the system of accounting may require.

A further object of the invention is to provide a ledger sheet properly ruled and designated to receive daily balances of transactions, having a space substantially unruled, approximating the size of the statement sheet to be superposed thereon, said statement sheet being properly ruled and designated to receive at the beginning a balance from the ledger sheet, and presenting daily and final balances to be transferred to columns on the ledger sheet properly designated to receive such items.

With these and other objects in view, the invention comprises certain novel arrangements of ruling and column designations as will be hereinafter more fully described and claimed.

In the drawings:

Figure 1 is a view of the ledger sheet with

the statement sheet superposed thereon and attached thereto for filing in combination.

Fig. 2 is a view of the ledger sheet with the statement sheet removed and without items appearing thereon.

60

In modern accounting systems it is customary to present to the customer periodically, as for instance, monthly, statements showing each item of purchase or other transaction during the period, with totals for the transaction of each day upon which the business was transacted, whether debit or credit, beginning with the balance, if any, carried over from the preceding period and ending with the balance at the termination of such period; and to employ ledgers into which are posted from the statement sheets the daily totals, and to carry out such daily totals in balances, so that at any time the ledger will show the exact balance, debit or credit, standing in the name of the customer. For the purpose of facilitating the proper entry of the daily transactions, daily

65

balances and total balances upon the statement sheet and the ledger sheet, the present invention provides a ledger sheet of such size and ruling that the statement sheet may be attached thereto and both filed together, to be withdrawn from the file and, still connected, inserted in a typewriting machine for the purpose of entering upon the statement sheet the transactions for a given day, and simultaneously transferring to the ledger sheet the daily totals, old and new balances; having before the operator simultaneously in the typewriting machine the statement sheet and the ledger sheet, thus preventing errors and adding to efficiency.

80

Specifically, a ledger sheet 10 is provided, having at one side a space 11 corresponding approximately to the size of the statement sheet 12, here shown at Fig. 1 as a monthly statement, which is the period usually and ordinarily covered in such statements.

95

Upon the statement sheet in column 13 will be entered the day of the month, which will be designated at 14 at the top of the statement. The first item appearing upon the statement sheet will be the balance transferred from the ledger sheet 10, in the case illustrated being the old balance appearing at the beginning of business for the month designated, and shown at 15. The old balance appearing at 15 on the ledger sheet 10 will be the net balance transferred from 110

100

column 16 of the statement sheet for the preceding month; so that the balance appearing at the top of the statement sheet for one month will correspond with the balance 5 appearing at the end of the statement sheet for the preceding month, which preceding balance has been entered at 17 on the ledger sheet.

Following the entry at 15 on the ledger sheet it will be noted that the debit totals of each day appearing upon the statement is entered in column 18 of the ledger sheet, and also that the credit of each date appearing upon the statement sheet will be entered 15 in column 19 of the ledger sheet. The amounts appearing under the designations upon the ledger sheet as "Old bal." and "New bal." will be, respectively, the old and new balances after the debits have been 20 added and the credits subtracted. It will also be seen that the net balance appearing at 20 on the statement sheet is the final charge appearing under "New bal." at 21 on the ledger sheet. There is no novelty 25 claimed in the present application in the manner of designating the columns of either the statement sheet or the ledger sheet, or of entering the charges, credits, or balances thereon, such accounting being the modern 30 accounting system. The invention in the present case resides, however, in so proportioning the ledger sheet that the statement sheet may be attached thereto and filed therewith, and inserted in a typewriting 35 machine in connection therewith, without obscuring upon either of the sheets the items, and facilitating reference to either the statement sheet or the ledger sheet during any predetermined period. While it is the 40 intent to use the invention by placing under the statement sheet 12 a similar sheet with an interposed carbon sheet whereby a carbon copy is secured, such carbon copy forms no part of the present invention and 45 provides simply a copy for filing in the accounting system of the trader, for future reference as to accuracy of any balances or items appearing upon the ledger sheet after the original statement sheet has been delivered to the customer.

In operation, at the time of the first transaction for a given period, as for instance the first transaction during a month, the ledger sheet of the customer is produced from the 55 file and a new statement sheet attached. The first entry upon the statement sheet will be the last item appearing upon the ledger sheet as the balance of the account. The transaction for the day will be entered in 60 itemized form upon the statement sheet, and the balance transferred to the ledger sheet, which, being completed, will be removed from the typewriting machine and, while

still attached, will be filed in whatever form of filing system is employed by the trader, 65 there to remain until another transaction is to be entered, whereupon the combined sheets are removed from the filing system, again inserted in conjunction in the typewriting machine, and the operation repeated. This is done as many times during the month or other period as it is found necessary to enter the daily or periodical transactions. At the end of the month or other accounting period, the statement sheet 70 is removed from the ledger sheet and the ledger sheet filed away in the filing system unaccompanied by a statement sheet, to remain so until another transaction necessitates the application thereto of a new statement sheet. 80

What I claim is:

1. The combination with a statement sheet, of a ledger sheet having a substantially unruled portion approximating the 85 size of the statement sheet, and a ruled portion visible when the statement sheet is superposed on the unruled portion, properly ruled and designated to receive balances appearing upon the statement sheet. 90

2. The combination with a statement sheet properly ruled and designated to receive items of transactions, of a ledger sheet having a portion adapted to receive the statement sheet attached thereto and superposed thereon, and another portion visible when the statement sheet is so superposed, properly ruled and designated to receive balances appearing upon the statement sheet. 95

3. A ledger sheet having one side substantially unruled and the opposite side ruled and designated to receive accounting balances, in combination with a statement sheet proportioned and arranged to be superposed upon the substantially unruled portion of the ledger sheet, and properly ruled and designated to receive items of balance from the ledger sheet and items of periodical transaction the totals of which appear upon such statement sheet and to be transferred to those columns of the ledger sheet designated to receive the totals from the statement sheet. 105

4. The combination with a statement 115 sheet of a ledger sheet having a substantially unruled portion approximating the size of the statement sheet and a ruled portion all parts of which are visible when the statement sheet is superposed upon the ledger sheet, said sheets being properly ruled and designated to receive data to and from each other. 120

In testimony whereof I affix my signature.

ROBERT RICHARD KING.
